UNITED STATES PATENT OFFICE

157,367

COIN RECEIVING DEVICE

Alexander M. Gordon, Providence, R. I., assignor
to Max L. Grant, Providence, R. I.

Application April 26, 1949, Serial No. 2,269

Term of patent 14 years

(Cl. D52—4)

To all whom it may concern:

Be it known, that I, Alexander M. Gordon, a citizen of the United States of America, residing at Providence, county of Providence, State of Rhode Island, have invented a new, original, and ornamental Design for a Coin Receiving Device, of which the following is a specification, reference being had to the accompanying drawing, forming a part thereof.

Figure 1 is a front elevational view of a coin receiving device showing my new design;

Figure 2 is a rear view;

Figure 3 is a side elevation; and

Figure 4 is a top plan view.

I claim:

The ornamental design for a coin receiving device, substantially as shown.

ALEXANDER M. GORDON.
